Patented July 26, 1921.

FIG. 1.

FIG. 2.

Inventor:

John Q Sherman

By Allen & Allen

Attorneys.

UNITED STATES PATENT OFFICE.

JOHN Q. SHERMAN, OF DAYTON, OHIO.

AUTOGRAPHIC REGISTER.

1,385,587.

Specification of Letters Patent. Patented July 26, 1921.

Application filed November 15, 1919. Serial No. 338,154.

To all whom it may concern:

Be it known that I, JOHN Q. SHERMAN, a citizen of the United States, and a resident of the city of Dayton, in the county of Montgomery and State of Ohio, have invented 5 certain new and useful Improvements in Autographic Registers, of which the following is a full, clear, and exact description, reference being had to the drawings forming 10 a part of this specification.

My invention relates to autographic registers of the type which roll up and store a full sized record of the transactions registered on the strips issued from the machine. 15 This type of register has been developed by me in the past and the present invention involves a simple structure of small expense which operates by a spring to roll up the record strip during periods when the main 20 paper feed is out of operation.

As has been developed by me, this mode of operation permits of the record strip being fed along with the regular duplicate strips, and accumulating in the casing during 25 the regular feed, thereby permitting it to be held in alinement with the other strips, and still providing for the complete winding or rolling of it, at the close of each feeding operation.

30 It is my object in my invention herein to reduce to very simple and compact form a record rolling device of the above character, and I accomplish my object by that certain construction and arrangement of parts to be 35 hereinafter more specifically pointed out and claimed.

In the drawings,

Figure 1 is a side elevation showing the essential features of my invention.

40 Fig. 2 is an end elevation of the record roll, showing its connection to the spring actuating device.

The casing of the autographic register is indicated at 1, in which casing is mounted 45 the main shaft 2 of the register. As shown in the illustration of my invention herein I feed the regular strips of paper including the record strip by means of a pair of pin bearing bodies or wheels 3 connected to the 50 shaft 2 at each end thereof and carefully alined with each other. The pins 4 on said bodies enter marginal perforations in the paper.

55 Mounted loosely on the shaft is a pulley or drum 5, which carries a ratchet 7. A spring pawl 6 mounted on one of the pin

wheels 3 normally bears against the ratchet 7, so that the revolution of the pin wheel will carry the drum with it.

A spring housing 8 containing a coiled 60 spring 9 is secured on a stud 10 in the side of the casing. On the housing 8 is wound a cable 11 which passes over an idler 12, and thence up to the pulley 5. When the operating handle 13 on the shaft 2 is revolved, the 65 ratchet and pawl device moves the pulley around so as to wind up on the cord and put the spring housing 8 under tension of the spring within.

A pin mounted on the casing is set so that 70 at the close of a feeding operation of the handle, this pin 14 will strike up the pawl thereby releasing the ratchet from connection with the driving shaft and permitting the spring to retract the cable and revolve 75 the spring housing. The ratchet will not fall back into mesh until the pin wheels have been moved to begin another paper feeding operation.

The roll 15 on which the record sheet A 80 is to be wound up is provided at one end with a recess 17, which houses a coiled spring 18. Into this recess fits a mounting pin 19, that at its outer end engages in a recess in the machine casing. 85

The other end of the roll is provided with a ratchet 20 which is pressed frictionally against the inner side of the spring housing 8, by means of the spring 18 pressing 90 against the inner end of the mounting pin. When the housing revolves it will carry with it the ratchet and the roll.

In order to prevent motion except in one direction of the roll, a pawl 21 is mounted 95 on the side of the casing, and pressed against this ratchet 20, so as to prevent clockwise motion of the roll.

The operation of the machine is thus evident. The operator revolves the feeding shaft by means of the handle which carries 100 the desired duplicate sheets out of the machine, and at the same time, moves the record sheet A into the compartment of the casing beyond the feeding devices, and over an idler 22. This last mentioned sheet accumulates during the feeding motion and hangs loosely. The spring operator, however, is at the same time energized and at the close of the feeding operation released, whereupon it rapidly rolls up the slack in 110 the record sheet.

The parts are proportioned so that the

spring housing revolves more than is necessary to wind up all of the accumulated record at any one feeding operation, and the remainder of the motion over and above that necessary to accomplish the tight winding is taken up by the frictional slip between the spring housing and the ratchet at the end of the record roll.

The parts of this mechanism are few and simple in operation, and the operation thereof will result in a tightly wound record strip of full size as compared to the issued strips.

It is not my desire that the claims that follow be limited beyond the inclusion therein of mechanical equivalents to the parts named, because of my failure above to point out the various substitutions of equivalents possible for the parts specifically described.

Having thus described my invention, what I claim as new and desire to secure by Letters Patent, is:—

1. In an autographic register, the combination with a rotary feed device for feeding a plurality of strips of paper together with a record strip, all of said strips to receive impression copies of the topmost one thereof, of a roll for storing the record strip, a rotating spring impelled body, and

30 a trip device controlled by the feed device for timing the motion thereof free of the feed device, said roll for storing the record being actuated by said rotating spring impelled body.

35 2. In an autographic register, the combination with a feed device for feeding a plurality of strips of paper together with a record strip, all of said strips to receive impression copies of the topmost one thereof, of a roll for storing the record strip, a rotating spring impelled body, means on the feed device for energizing and releasing the spring impelled body, said roll for storing the record being actuated by said rotating

45 spring impelled body.

3. In an autographic register, the combination with a feed device for feeding a plurality of strips of paper together with a rec-

ord strip, all of said strips to receive impression copies of the topmost one thereof, of a roll for storing the record strip, a rotating spring impelled body, means on the feed device for energizing and releasing the spring impelled body, said roll for storing the record being actuated by said rotating spring impelled body, said roll having a spring for frictionally retaining it against the said rotating body.

4. In an autographic register, the combination with a feed device for feeding a plurality of strips of paper together with a record strip all of said strips to receive impression copies of the topmost one thereof, of a roll for storing the record strip, a rotating spring impelled body, means on the feed device for energizing and releasing the spring impelled body, said roll for storing the record being actuated by said rotating spring impelled body, and means connected to the roll for preventing its movement except in one direction.

5. In an autographic register, the combination of a rotary feed device for feeding, and maintaining in accurate registry with each other a plurality of strips of paper including a record strip, of a roll for storing the record strip, a rotating spring impelled body and means in connection with the feed device for releasing the said rotating body, at the close of each feeding operation of the machine for rotation entirely free of the feeding device.

6. In an autographic register, the combination of a rotary feed device for feeding, and maintaining in accurate registry with each other a plurality of strips of paper including a record strip, of a roll for storing the record strip, a rotating spring impelled body, said feeding means having devices for winding up said spring impelled body and releasing it for operation entirely independent of the motion of the feed device, said release being timed to occur at the close of each feeding operation of the machine.

JOHN Q. SHERMAN.
